UNITED STATES PATENT OFFICE.

ALONZO P. CONNOLLY, OF CHICAGO, ILLINOIS.

DESIGN FOR A BADGE.

SPECIFICATION forming part of Design No. 22,597, dated July 11, 1893.

Application filed December 5, 1892. Serial No. 454,411. Term of patent 7 years.

To all whom it may concern:

Be it known that I, ALONZO P. CONNOLLY, a citizen of the United States, residing at Chicago, in the county of Cook and State of Illinois, have invented or produced a new and original Design for a Badge, of which the following is a specification, reference being had to the accompanying drawings, forming a part thereof.

10 Figure 1 shows the obverse, and Fig. 2 the reverse side reduced in diameter.

The leading features of my design consist of pictorial scenes of the War of the Rebellion, and the star forms the badge of the Grand Army of the Republic; the detail arrangement being as follows: The central part of the tablet on the obverse or front side is divided into three triangular spaces, A, B and C, inclosed by the circular line a . In the foreground of space A, is represented a section of a Confederate water battery engaging Fort Sumpter, shown in the distance. In space B is represented the naval engagement between the *Monitor* and *Merrimac*; and in space C is represented the surrender of Lee to Grant at Appomattox. In the circular space D are represented various scenes and detail features of the battle of Gettysburg, as follows: To the left is a battery, a^2 , going into action; at the top a caisson, a^3 , is shown as

having just exploded, a number of soldiers being shown in different attitudes; to the left, a^4 , is represented a group of prisoners being escorted to the rear, and at the bottom, underneath the surrender of Lee, is a field hospital scene, b , in which wounded soldiers together with medical attendants and stretcher-bearers are shown about a stack of wheat. The border consists of forty-four stars, b' , representing the States of the Union disposed at intervals in the space between the circular lines $b^2 b^3$. On the reverse side is represented the star design, g , of the badge of the Grand Army of the Republic, inclosed by the double border lines $g' g^2$. In the space between these lines are stars h representing the thirteen original States of the Union.

Having thus described my design for a badge, what I claim is—

1. The design for a badge, substantially as shown and described.
2. In a design for a badge, the obverse, substantially as shown and described.
3. In a design for a badge, the reverse, substantially as shown and described.

ALONZO P. CONNOLLY.
